UNITED STATES PATENT OFFICE.

AUGUST H. YOUNG, OF COUNCIL BLUFFS, IOWA.

CLOSET-BOWL.

1,177,221.

Specification of Letters Patent. Patented Mar. 28, 1916.

Application filed December 31, 1915. Serial No. 69,555.

To all whom it may concern:

Be it known that I, AUGUST H. YOUNG, a citizen of the United States of America, and resident of Council Bluffs, in the county 5 of Pottawattamie and State of Iowa, have invented certain new and useful Improvements in Closet-Bowls, of which the following is a specification.

This invention relates to baths and closets 10 and particularly to closet bowls.

The invention has for its object the provision of novel means for collecting moisture which would otherwise descend to the floor of the room containing the closet bowl, 15 the said collecting means being in position to permit the ready removal of the moisture by absorption as by the use of a sponge, cloth or other agency.

It has been found that owing to the fact 20 that the closet bowl contains water, the bowl is usually colder than the surrounding atmosphere, so that the warm air contacting with the surface of the bowl causes condensation which as it progresses, moistures 25 collects to such an extent as to descend by gravity and in bowls of ordinary construction, this moisture finds its way to the floor where it spreads and causes unsanitary condition which is the purpose of this invention 30 to eliminate.

It is a further object of this invention to provide a closet bowl of the character noted, which will prove efficient and satisfactory in use, proving at the same time comparatively inexpensive to manufacture.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this specification wherein like characters denote corresponding 45 parts in the several views, and in which—

Figure 1 illustrates a vertical sectional view illustrating a closet bowl embodying the invention; Fig. 2 illustrates a sectional view on the line 2—2 of Fig. 1; Fig. 3 illustrates a sectional view on the line 3—3 of Fig. 2; Fig. 4 illustrates a sectional view on the line 4—4 of Fig. 2; and Fig. 5 illus-

trates a top plan view of the base of the bowl.

In these drawings 6 denotes the closet bowl which may be of any ordinary construction and as the configuration of the bowl and the internal mechanism may be of those types now in common use, a detailed description of such features will not be given herein.

The closet bowl in the present embodiment of the invention has a base flange 7 which extends from the base portion of the 65 bowl and entirely around it. The said base flange is recessed or concaved as at 8 to form a trough-like structure designed for the collection of moisture. At certain points, the flange is provided with bosses or raised 70 portions 9 forming partitions dividing the trough-like structure into sections and the bosses 9 (which are preferably of a height to align with or extend above the upper surface of the base of the flange) may have 75 apertures such as 10 for the reception of bolts or other securing means or the said bosses or partitions may have slots 11 for the reception of such securing devices. By reason of the construction described, the 80 apertured bosses provide means for the reception of the said anchoring devices, yet precluding the escape of the moisture or water from the trough-like structure and furthermore preventing deterioration which 85 might occur should the water find its way to the joint formed by the anchoring means.

From an inspection of the drawing, it will be apparent that the sections of the trough-like structure will serve to collect water and 90 that by the application of an absorbent material, the water so collected may be removed, thus insuring against the distribution of the said water over any area of the floor on which the closet bowl is stationed. 95

I might also state that the recessed flange above referred to may be rigidly secured to any type of closet bowl now in use, but is not interchangeable.

I claim:

1. In a closet bowl having a base flange, said base flange being recessed to form a trough-like structure, bosses extending transversely of the recessed portion of the flange dividing the trough-like structure into sections, said bosses having apertures therein

for the reception of anchoring means, and said bosses being of a height equal to the upper surface of the said flange.

2. In a closet bowl having a base flange, said base flange being recessed to form a trough-like structure, bosses extending transversely of the recessed portion of the flange dividing the trough-like structure into sec-

tions, said bosses having apertures therein for the reception of anchoring means.

In testimony whereof, I affix my signature in the presence of two witnesses.

AUGUST H. YOUNG.
